UNITED STATES PATENT OFFICE.

CARL AXEL WILHELM HULTMAN, OF STOCKHOLM, SWEDEN.

AUTOMATIC TELEPHONE-EXCHANGE SYSTEM.

1,239,011.

Specification of Letters Patent.

Patented Sept. 4, 1917.

Application filed May 29, 1914. Serial No. 841,956.

To all whom it may concern:

Be it known that I, CARL AXEL WILHELM HULTMAN, a subject of the King of Sweden, and a citizen of Sweden, residing at 24 5 Jakobsbergsgatan, Stockholm, in the Kingdom of Sweden, have invented certain new and useful Improvements in Automatic Telephone-Exchange Systems, of which the following is a specification.

10 The present invention relates to an automatic and semi-automatic telephone exchange system and has as its principal object the provision of a system having a minimum number of parts, all of a simple 15 construction allowing a sure working and low costs of establishment.

A further object of the invention is to provide automatic and semi-automatic telephone exchange systems using switches, particularly final or connector switches, of large 20 capacity.

A third object is to obtain a simple and cheap construction and compact arrangement of the switches when the same are of 25 large capacity in such automatic and semi-automatic systems.

With the above and other objects in view, the subscriber's lines are arranged to terminate in bare wires, which are laid parallel 30 and can run in either horizontal or vertical direction. The sets of wires corresponding to the various lines are so arranged as to be identified in a two coördinate system. A group of lines arranged in this manner is 35 accessible to a number of incoming lines each connected to a switch having selective movement transversely to said wires in the two directions of said coördinate system. The switches may be operated by means of 40 continuously rotating shafts and electro-magnetic clutches controlled by a register device which, after having been set by the calling subscriber or operator according to the number wanted, determines the amount 45 of movement of the switch in each direction.

Figure 1 is a diagrammatic view showing a number of bundles of wires in which the subscriber's lines terminate arranged according to my system, and also showing the means of supporting the wires and the contact making portion of a connector switch according to my system shown in connection 50 with one of the sets of subscriber's wires.

55 Fig. 2 is a diagrammatic view in which each set of three wires for a given subscriber is represented by a small circle or dot, this

figure and Fig. 1 being taken transverse to the length of the wire bundles and Fig. 2 showing a group of 100 such bundles. 60

Fig. 3 is a diagrammatic view indicating the space transversely of the wire bundles occupied by current groups such as is shown in Fig. 2, Fig. 3 consequently indicating an arrangement for 10,000 subscriber lines. 65

Fig. 4 is a diagrammatic view illustrating the arrangement of 60,000 lines in groups of 10,000 each, 30,000 being shown at I and 30,000 more being shown at II.

Fig. 5 is a diagrammatic view of the arrangement for a million subscriber lines.

Fig. 6 is a view showing the electrical diagram of the auxiliary switch used in my system.

Fig. 7 is a view of one of the number 75 switches used in my system.

Fig. 8 is an elevational view of one of the switching organs or connector switches used in my system.

Fig. 9 is a cross sectional view of the 80 switch shown in Fig. 8.

Fig. 10 is a diagrammatic view of the electrical circuit used in the switch shown in Figs. 8 and 9.

Fig. 10^a is a view showing the relative ar- 85 range of the contacts 1₁, 1₂, and 1₃.

Referring to Fig. 1, a' and b' are connected to the two branches of the double subscriber's line and c' is the pilot wire, which can be omitted in case certain 90 functions of the apparatus are thought unnecessary. The conducting wires are separated from each other by means of insulating partitions w arranged in any way and fastened in the known manner to frames of iron or 95 any other suitable material. Fig. 1 illustrates an ebonite partition w on which the conducting wires are fastened in grooves therein; but any convenient arrangement of the ebonite partition with relation to the 100 conducting wires may be used. A plurality of sets of wires a', b', c' are shown in Fig. 1, but only one of the partitions w.

K is a bar shown in detail in Fig. 1 and forming part of a connecting switch shown 105 in Figs. 8 and 10. The three springs 1, 2 and 3 are carried by bar K with the lines 1', 2' and 3' respectively appertaining thereto.

If after a certain interval z this bar K 110 is carried from an initial position for instance in a horizontal direction and thereafter in vertical direction to a certain height, the springs of this bar will be connected to

the three wires a' , b' and c' of a certain subscriber. If the wires to the bar K are already connected to another subscriber, these two subscribers will be connected with each other. It is evident that by placing the bar into corresponding positions in horizontal and vertical directions it may be connected with all wires of the subscribers if any number of such wire sections are brought together in this manner.

If in Fig. 2 each point indicates the three wires of one subscriber and these three wires occupy an area of 10 mm.^2 , 100 subscribers will require an area of about 100 mm.^2 and 10,000 subscribers such an area of about 1 m.^2 (comp. Fig. 3).

If an exchange office of 30,000 subscribers supposed, the contacts of these subscribers will occupy an area, 1 meter in height and 3 meters in length, presumed that the 10,000 sections are placed at the side of each other as shown in Fig. 4.

60,000 subscribers presumed, three further 10,000-sections can be placed at the side of the former, but the three latter may also as shown in Fig. 4 be put together in a separate section and a movable bar arranged for each of the 30,000 sections indicated in rows I and II. The wires in a given bundle 30 may also be arranged in rhomboidal position instead of in a triangular one.

In this respect it has been empirically settled that the number of switching organs (number switches) necessary for 10,000 subscribers amounts to 2%, thus 200 of such organs (number switches) and for 30,000 subscribers only 600 switches.

If 300 switching organs are arranged above the subscribers' wires and 300 below and each number switch has a longitudinal extension of 40 mm., the length of the wires will amount to about 12 meters. If the number of switches be increased even to 1200, the length will amount to only 24 meters which is essentially below the dimensions, required by the automatic systems known hitherto.

Further it is evident that the length of the subscriber's wires not covered is dependent on the necessary number of switching organs or connector switches.

In the following it will be explained how to move the switching organs in a practical manner in order to find the wire bundles of the telephone desired.

This can be performed in different ways. Therefore, only the most suitable embodiment will be described.

In my system a calling subscriber is automatically connected with an auxiliary switch mechanism each of which controls the movements of a switching organ or connector switch. The use of automatic preselectors being, however, common in this art, they 65 are not shown in the drawing. The im-

pulses for operating the auxiliary switches are sent over the two sides of the calling subscriber's line by means of the usual dial impulse senders, but other methods of sending may be adopted as desired.

Therefore, if the calling subscriber automatically receives connection with an unengaged auxiliary switch and switching organ and his pilot wire is indicated as engaged by ground connection he transmits by means of a common number disc as many impulses as the 10,000 digit of the number of the subscriber requested indicates. Referring more particularly to Figs. 6 to 10, the following will give information about the 75 manner of operating the various switches so that a calling subscriber can select and connect his own line in talking relation with that of any other line in the system.

In Figs. 6, I to VI inclusive indicate six 85 section switches forming part of an auxiliary switch, the movable contact levers d^1 , d^2 , d^3 , d^4 , d^5 , and d^6 of which are arranged on a common shaft c . Each section switch has six fixed contacts 1 to 6 inclusive.

The different section switches I—IV of a given auxiliary switch are connected in the following manner to different parts of the system.

Switching section I: One side of the calling subscriber's line a comes in by the movable switch lever d' and goes out by the contact 6 when the auxiliary switch is in the position for talking; the contacts 1—5 are connected with each other and with a 100 line-relay L^1 connected to one of the poles of the battery B^1 , the other pole of the battery being grounded. The relay L^1 operates the two contacts f^1_1 and f^1_2 . f^1_1 is on the one hand connected with the grounded 105 battery B^2 and on the other hand with the contact f^2_2 , while f^1_2 is connected on the one hand with f^2_1 and the earth, on the other hand with the contact levers d^3 of the section III.

Switching section II: The second side of the calling subscriber's line b comes in by the movable contact lever d^2 and goes out by the contact 6 of section II when the parts are in the talking position; the contacts 1—5 are connected with each other and with a second line relay L^2 connected with battery B^1 . The relay L^2 operates the two contact springs f^2_1 and f^2_2 . f^2_1 completes when closed the connection to earth of the 120 contact levers d^4 and d^6 of the sections IV and VI.

Switching section III: The contacts 1—5 are connected to relays A, B, C, D and E respectively, connected to a grounded battery B^5 these relays each operating a number switch such as is shown in Fig. 7 in the manner further explained below.

Switching section IV: The contacts 1—4 of this section are connected with the con- 130

tact 5 of the switching section V by means of the switches k and k^1 , and with the switching-relay R^6 , the latter being connected up to the grounded battery B^3 .

5 *Switching section V:* The contact lever d^5 is grounded and the contact 5 is connected with the two switches k and k^1 already mentioned.

10 *Switching section VI:* The contact 5 is connected with the relay R connected up to the grounded battery B_4 , this relay operating the starting contact K_5 . This contact is arranged between the earth and (Fig. 10) a starting-relay L .

15 In the following the contacts belonging to the different switching sections are thus indicated that for instance VI: 4 is the contact 4 of the switch VI.

The contacts III 6, IV 5, IV 6, V 1, V 2, 20 V 3, V 4, V 6, VI 1, VI 2, VI 3, and VI 4 serve no special purpose in the system described.

25 There is one relay such as A, B, C, D, or E and one number switch for each significant figure of the largest number in the system and the relays A, B, C, D and E operate each one number switch (Fig. 7) in such manner that if three impulses are given to the relay A, the disk S of the corresponding number switch moves three steps, whereupon the contact connections 1, 2 and 3 (Fig. 7) are grounded, but not the remaining ones.

30 The number switch will be further described below. The auxiliary switch and its sections I—IV work essentially in the following manner:

35 Let it be supposed that the called subscriber has the number 25786. The calling subscriber moves his number dial, placed at the speaking apparatus, to 2, whereupon—in the system in which the number of impulses are one unit below the corresponding figure—one impulse flows through the wire 40 $a: d'$ contact I 1, L^1 , B^1 to earth. The contact f^1_2 closes, whereupon a current from the battery B^5 flows through A, III 1, d^3 , f^1_2 . The single impulse through A moves by one step the corresponding 10,000 number or figure switch (Fig. 7) whereat its contact 1 is grounded. On moving back the number disc on the subscribers apparatus an impulse is transmitted through the b -wire, whereupon the current flows through 45 d^2 , L^2 and B^1 . The contact f^1_2 closes, whereupon the contact levers d^4 and d^6 are grounded. d^4 is, however, connected with relay R^6 and battery B^3 via IV 1 and the stepping relay R^6 is thus excited. The relay R^6 operates to turn the shaft c of the auxiliary switch so that contact arms d^1 , d^2 , d^3 , d^4 , d^5 , and d^6 shall be stepped around from one contact such as 1 to the next contact such as 2, but it is understood that the 50 relay turns the shaft but one step for each

flow of current through the relay and then only at interruption of the current. However, the contact f^1_2 is held closed only momentarily so that the shaft c is stepped up promptly except as mentioned below. 70 This relay thus operates the shaft c of the auxiliary switch so that the shaft is moved by one step after an impulse through R^6 causing the levers d to take the position 2.

The calling subscriber now operates the 75 1,000 figure switch moved by the relay B . On carrying his number dial to the digit 5 of the 10,000-figure he transmits four impulses through a wire thus exciting L^1 four times and correspondingly over d^3 , III 2 excites the relay B four times. B thus operates the 1,000-figure switch so that it is moved four steps causing the contacts 1 to 4 of the 1,000-figure switch similar to the one in Fig. 7 to be grounded. 80

85 On moving back the subscriber's dial an impulse operates relay L^2 in the same manner as above described, whereupon the auxiliary switch is so operated by R^6 that arms d^1 , d^2 , d^3 , d^4 , d^5 and d^6 each occupies its contact 3.

90 Through the contact III 3 C, the subscriber next sends six impulses, causing the contacts 1-6 of the 100-figure switch to be grounded. 95

95 In the same manner the 10-figure switch and unit figure switch are then moved by seven and five steps respectively. If, however, the subscriber's disk or disc is moved back into the initial position after these 5 100 impulses last mentioned, the auxiliary switch I—VI must not enter into its sixth position—speaking-position—when the connection is effected, that is to say before the switching organ K on the connecting switch has 105 reached the subscriber desired. I provide for this feature in a manner described below.

110 The figure switches are simple and easily movable, having a spring moving back device and thus arranged that if for instance the figure digit is 5 all the digits from 1—4 together are connected with the earth.

115 Such a figure switch is shown in diagram in Fig. 7. 1, 2 and 3 inclusive are common flat contact-springs of a suitable length. The grounded disc S rotating for instance by two steps from the initial position (the corresponding digit is then 3), the contacts 1 and 2 are connected with earth. The disc S may also be substituted by a lever whereby only the contact at which the lever stops is connected with the earth. 120

125 The different contacts 1 to 10 of the five figure switches are connected to contacts of the contact-bars l_1 , l_2 , l_3 , l_5 , and l_6 and (Fig. 125 8 or 10) in such a manner that l_1 , l_2 , and l_3 respectively are connected with the ten thousands, one thousands and unit figure switches, but l_5 and l_6 respectively with the 100- and 10 figure switches. 130

As above mentioned the auxiliary-switch shown in Fig. 6 must not enter into the last or talking position before the switching organ has reached the wires to the called subscriber, at the last moving back of the disc of the calling subscriber into the initial position the relay R^6 must not immediately release and so operate the shaft, but the current in relay R^6 must be maintained temporarily, which is obtained by the contact 10 IV 5 not being connected with R^6 and by releasing the two contacts k and k_1 which close a circuit through R^6 and b_3 when d^5 is on contact 5.

15 These two contacts are connected in parallel and so arranged that k is closed as afterward described when the switching organ K is moving (Figs. 1 and 8) upward, while K_1 is normally closed but is released as soon 20 as K moves up. If afterward connection with the subscriber requested is obtained the contact k is released by means of a pilot relay, whereby R^6 loses its current. k_1 is released already before k , k , being released at 25 the end of the horizontal movement of K so that R^6 loses its current upon operation of K_1 , and thus operates the auxiliary switch which enters into its sixth position (speaking position). R^6 is thus arranged to operate 30 on losing its current. If now the called subscriber is not engaged, a pilot relay is automatically shifted and connects the subscribers; otherwise the relay is not shifted and the calling subscriber receives the commonly used signal denoting that the called 35 subscriber is "engaged." In the fifth position of the auxiliary switch the switching organ K is operated as above mentioned and in such a way as to move to the wire of the 40 called subscriber before the auxiliary switch enters into its position 6. This is obtained by the fact that when the next to the last impulse flows by the b -wire a circuit is closed through d^6 , VI 5, relay R and battery B^4 .

45 The contact k^2 will thus be closed whereby the movement of the switching organ is initiated and carried automatically as further described below.

Y are relays operating in the usual manner for moving back the figure switches and the auxiliary switch into the position of rest, either during the switching if released or after closing the conversation. If the subscriber interrupts the switching then both 50 line relays L_1 and L_2 are energized and springs f^1_1 and f^2_2 at once snap together and all movable parts are moved back into the position of rest by means of these relays Y in a suitable manner. The moving back 55 device being unessential to the invention, a particular description thereof is superfluous.

These relays Y may if desired be combined into a single moving back relay.

The Figs. 8 and 9 show the construction 60 of the switching organ K and the manner of

carrying it to the wire of the subscriber in question.

It consists of two parts, one part V (Fig. 8), preferably moved in horizontal direction by means of motive power and a raising device K, moved in vertical direction.

The part V (which may have different embodiments) is shown according to Fig. 8 as a carriage on four wheels moving between the bars s_1 , s_2 , s_3 and s_4 which are fastened 75 to a convenient support or the wall F. This wall also supports four strips l_0 , l_1 , l_2 , l_3 provided with insulated contacts and a guiding strip l_{1v} having wave-like notches u in which a pulley such as r guided by a spring and fastened to the carriage V will catch and assure a certain position. r_1 is the endless trace fastened to the carriage and running over guiding discs and over the driving pulleys R_1 and R_2 . The carriage V is provided 80 with two parallel strips n_1 and n_2 between which the movable switching organ K moves in a vertical direction wherein it is guided by ebonite pulleys m fastened thereto and two pulleys t_1 and t_2 fastened to the carriage. 85 The contact device K is movable along the frame R_0 between the bars s_5 and s_6 .

R_0 (Fig. 8) can if desired be easily balanced and moves up and down operated by the trace running over the driving pulleys 95 R_3 and R_4 and at the bottom over the guiding pulleys r_3 , r_4 , r_5 and r_6 .

The cord q , running over a pulley and loaded with a weight W and further over the pulley x down to the contact device K 100 contains the three wires of the switching organ K, the two branches 1 and 2 and the pilot wire 3 belonging thereto (Fig. 1). By this new arrangement the number of the speaking line contacts after the switching 105 operation is completed will not exceed after connecting two subscribers of the automatic system that of hand operated systems as the switching is performed in the same manner only with one connecting wire.

110 The construction features of the switching organ (wire switch) being described and the manner of moving it in horizontal and vertical direction to any subscriber of the whole network of any number of the subscribers, it 115 only remains to show how to make it stop at the very subscriber's number requested.

Fig. 10 shows this; k_2 is the starting-contact serving for the starting of the starting relay L which starts the carriage V and the 120 contact device K (also compare Fig. 6) (in semi-automatic systems this momentary closing is operated by means of a starting-key). If the relay L at closing the contact k_2 obtains a momentary current from the battery 125 B^6 the contacts 11 and 12 are closed, 13 and 12 released and 14 and 15 closed.

When 14 and 15 are closed a magnetic clutch will be operated, clutching the driving pulley R_1 (Fig. 8) to a continuously ro- 130

tating shaft; the carriage V (Fig. 8) then has a motion forward, whereby the four springs f_0, f_1, f_2 and f_3 arranged on the carriage and connected with each other are moved along the fixed strips l_0, l_1, l_2 and l_3 (Figs. 8 and 10). Strips l_1, l_2 and l_3 are all provided with individual contacts—as shown at l_3 in Figs. 8 and 10—which are connected with the contacts 1—10 of the different figure switches for the 10,000, 1,000 and units places according to Fig. 7, whereas l_0 has a continuous contact conductor thereon.

f_0 is a slip spring connecting the contact 15 of the springs f_1, f_2, f_3 and the starting relay L as l_0 is connected with I.

It is evident that as soon as L loses its current the contact 14, 15 is broken and the horizontal motion of V and K ceases as the magnetic clutch is released. Now so long as one of the springs f_1, f_2 or f_3 is moving over grounded contacts at the bars l_1, l_2 , or l_3 so long the earth connection of the relay L through the bars l_1, l_2 , or l_3 will last and the 25 horizontal motion will continue.

The contacts on the bars l_1, l_2 and l_3 are thus arranged, that l_1 is provided with 10 contacts, spaced in such manner that after one contact on the bar l_1 ten contacts from 30 the bar l_2 are following, then a new contact on l_1 and ten contacts on l_2 and so on. The contacts on the bar l_3 are arranged in exactly the same manner. After every contact on l_2 ten contacts on l_3 are following, then a new contact on l_2 and ten contacts on 35 l_3 and so on.

In the example given—calling the number 25786—the 10,000-figures have been switched to earth by the first figure switch. 40 As l_1 determines the 10,000-figures by means of its contacts as above described the carriage V would stop at a place corresponding to the figure 20,000 but if the 1,000—4000 is switched to earth by the 1,000-figure switch, L thus continues to obtain current. The carriage V would because of this stop at the next contact at l_2 not grounded, that is to say at the fifth contact corresponding to 45 25,000, because at the fifth contact at l_2 L obtains no further current, but by the contacts at l_3 , indicating the units of the figures contacts 1 to 5 are switched to earth and the carriage stops at the sixth unit space on the contact corresponding to the number 25,000 50 (this because the relay L loses its current by breaking of the earth connection at l_3).

As the contacts 11 and 12 when L was operated were closed, the relay R^7 was operated by means of the battery B^7 and obtained a holding current via the contacts 18 and 19 and f_6 whereby 16 and 17 continue closed until the end of the vertical movement.

As later the relay L at completing the 65 horizontal motion lost its current the start-

ing relay R_8 for the vertical movement of K is switched to earth via 12, 13 and 16, 17 and B^7 and energizes whereby the contacts k (compare Fig. 6) and 20, 21 are closed.

By closing the contacts 20 and 21 a magnetic clutch of the pulley R_3 (Fig. 8) and its shaft is switched on. The bar R_0 and the contact device K (Fig. 8) then move upward. By closing the contact k (Fig. 6) the auxiliary switch cannot yet reach the speaking position, although at the first motion of K upward k_4 is released by a relay not shown. On the motion upward of the bar R_0 the springs f_4, f_5 and f_6 , connected with each other, slide on the strip l_4 and the contacts on the strips l_5 and l_6 respectively, these bars being shown horizontally in Fig. 10 for convenience in illustration but they are actually arranged vertically as in Fig. 8.

f_4 is a slip spring connecting the contact 35 of the springs f_5 and f_6 and the relay R_7 during the moving, as l_4 is connected to this relay.

The contacts of l_5 connected with the contacts 1 to 10 of the 100-figure switch control 90 the 100 figures and as f_4 is to stop at the 700-figure, the contacts 1—6 are switched to earth. The bar R_0 , however, can only stop when R_7 loses its current as the contact between 16 and 17 then is broken; R_8 loses its current 95 and the contact 20, 21 is broken, causing the pulley R_3 to be released. Thus R_0 cannot stop at 700; for the 10-figure of the number requested is 8 and because of this the contacts 1—7 of the 10-figure switches are 100 switched to earth on account of which the bar R_0 only stops at the eighth tens-figure, as it is only at this place R_7 and R_8 lose their current. Relay R_8 is then switched off and the contact device K stops and remains 105 switched to the wires of number 25786. As k also is now released owing to the loss of current in R_8 — k_4 was already released as mentioned—the auxiliary switch enters into the speaking-position (Fig. 6) for now only 110 does the current through R^6 end, causing the auxiliary switch to take one step.

The number switching may be effected quite independent of the relative position of the figures to each other.

For example in the example given with the number 25786 it is possible to switch in the wires in the bundle first on 20,000, then on 25,000, next on 25780 and finally on the unit figure.

If a semi-automatic system is sufficient the arrangements will be very simple and even all impulse transmissions may be avoided. Instead of the arrangement according to Fig. 6 a simple key device will be 125 used.

It should be observed that the switching organ or the wire switch cannot be used for too large subscriber numbers exceeding 10,000 to 30,000 subscribers.

For such large subscriber-numbers it is necessary to divide the number of subscribers in certain sections or substations separated from each other. In order to 5 switch among these stations a special group switch should be arranged in the known manner adjusting automatically to the section or substation requested at which the switching will be completed as above described.

10 What I claim is:—

1. In a telephone system in combination a plurality of bare wires, a plurality of subscribers' lines connected to said wires, said 15 wires extending along the sides of a space of parallelogrammatic cross-section, switching organs movable along the sides of the said parallelogram and adapted to connect with the wires corresponding to any called 20 subscriber, figure switches connected to said switching organs, and means for connecting, said wires being parallel and having such a length that a large number of switching organs may coöperate therewith, said organs 25 being movable perpendicularly into the space outlined by said wires as well along one side thereof, and figure switches for regulating the movement of said switching organs, said figure switches comprising 30 a bank of contacts and means for grounding said contacts in such a manner that the contacts corresponding to the digits of the number of the called subscriber's line shall be grounded prior to operation of the switching organ, whereby neither these wires nor 35 the figure switches will come into speaking-connection with the intermediate wires.

2. In a telephone exchange system, a plurality of lines, contact wires connected to 40 said lines and extending parallelly through a space of a parallelogrammatic cross section, the sets of wires corresponding to the various lines being so arranged as to be identified in a two coördinate system, contact wipers having selective movement trans- 45 versely to said wires in the two directions of said coördinate system and means for moving said contact wipers.

3. In a telephone exchange system, a plurality of outgoing lines of a switching stage, 50 contact wires connected to said lines and extending parallelly through a space of parallelogrammatic cross section, the sets of wires corresponding to the various outgoing lines being so arranged as to be identified 55 in a two coördinate system, a number of incoming lines each adapted to be connected with any of said outgoing lines, a number of switches each connected with one of said incoming lines and having selective move- 60 ment transversely to said wires in the two directions of said coördinate system and means for operating said switches.

4. In a telephone exchange system a plurality of lines, contact wires connected to 65 said lines and extending parallelly through a space of a parallelogrammatic cross section, the sets of wires corresponding to the various lines being so arranged as to be identified in a two coördinate system, a 70 switch having selective movement transversely to said wires in the two directions of said coördinate system, and means for operating said switch, and a register device governing the movement of said switch. 75

5. In a telephone exchange system, a plurality of lines, contact wires connected to 80 said lines and extending parallelly through a space of a parallelogrammatic cross section, the sets of wires corresponding to the various lines being so arranged as to be identified in a two coördinate system, a 85 switch having selective movement transversely to said wires in the two directions of said coördinate system, continuously rotating shafts, electro-magnetic clutches, means for moving said switch by operating said clutches and a register device controlling the amount of movement of said switch. 90

In testimony whereof I have affixed my signature in presence of a witness.

CARL AXEL WILHELM HULTMAN.

Witness:

GRETA PRIEN.
